(57) **CLAIM**

The ornamental design for an aerosol delivery device power unit as shown and described.

DESCRIPTION

FIG. 1 is a bottom perspective view of the aerosol delivery device power unit showing the new design;

FIG. 2 is a top perspective view of the aerosol delivery device power unit;

FIG. 3 is another top perspective view of the aerosol delivery device;

FIG. 4 is a front elevational view of the aerosol delivery device power unit;

FIG. 5 is a rear elevational view of the aerosol delivery device power unit;

FIG. 6 is an elevational view of a side of the aerosol delivery device power unit;

FIG. 7 is an elevational view of the opposing side of the aerosol delivery device power unit;

FIG. 8 is a top plan view of the aerosol delivery device power unit; and,

FIG. 9 is a bottom plan view of the aerosol delivery device power unit.

The broken lines shown in the drawings depict portions of the aerosol delivery device that form no part of the claimed design.
